ELECTRICAL CONNECTOR HOUSING

John H. Krehbiel, Downers Grove, Ill., assignor to Molex
Products Company, Brookfield, Ill., a corporation of
Illinois

Filed July 14, 1961, Ser. No. 65,922

Term of patent 14 years

(Cl. D26—1)

FIG. 1 is a perspective view of an electrical connector housing, showing my new design in assembled relationship;

FIG. 2 is an exploded perspective view;

FIG. 3 is an exploded side elevational view;

FIG. 4 is an end elevational view of the left half of the connector shown in FIG. 2 looking toward the left; and

FIG. 5 is an end elevational view of the right half of the connector shown in FIG. 2 looking toward the right.

I claim:

The ornamental design for an electrical connector housing, substantially as shown and described.
